(57) **CLAIM**

The ornamental design for the floor section module for entrance floor, as shown and described.

DESCRIPTION

FIG. 1 is a perspective view of the floor section module for entrance floor, with a single floor section module shown in an elevated position.

FIG. 2 is a top view of the floor section module of FIG. 1.

FIG. 3 are left and right side views of the floor section module of FIG. 1.

FIG. 4 are front and rear views of the floor section module of FIG. 1.

FIG. 5 is a perspective view of the floor section module of FIG. 1; and,

FIG. 6 is a bottom view of the floor section module of FIG. 1.

The broken lines shown throughout these figures are for illustrative purposes only and form no part of the claimed design.

1 Claim, 4 Drawing Sheets
